UNITED STATES PATENT OFFICE.

HARDIN M. HUGHS, OF McCOMB, OKLAHOMA.

WIRE-SECURING APPLIANCE FOR FENCE-POSTS.

1,108,990.

Specification of Letters Patent.

Patented Sept. 1, 1914.

Application filed August 14, 1913. Serial No. 784,844.

To all whom it may concern:

Be it known that I, HARDIN M. HUGHS, a citizen of the United States, residing at McComb, in the county of Pottawatomie 5 and the State of Oklahoma, have invented certain new and useful Improvements in Wire-Securing Appliances for Fence-Posts; and I do hereby declare the following to be a full, clear, and exact description of the invention, such as will enable others skilled 10 in the art to which it appertains to make and use the same.

This invention relates to securing means for fence posts, and contemplates the provision of a holder adapted to be secured to metal fence posts and adapted to secure the vertical and horizontal wires of a woven or barbed wire fence to said posts.

Another object of my invention is to provide means for securing the holder to the fence post.

Another object of my invention is the provision of a wire holder providing means for preventing movement of the same relative 25 to the post, and providing means for attaching a securing wire, whereby the holder may be secured to a post.

A still further object of my invention is the provision of a device of the class described which will be simple, durable, very 30 efficient in operation and comparatively inexpensive to manufacture.

With these and other objects in view the invention consists in the construction, combination and arrangement of parts herein-after more fully described and claimed and illustrated in the accompanying drawing, in which like characters of reference indicate like parts throughout the several figures, 40 and in which,

Figure 1 represents a side elevational view of a fence post constructed according to my invention, showing the wire holder in operation thereon, Fig. 2 represents a 45 front elevational view of the wire holder showing the same in operation on a fence post, Fig. 3 represents a side elevational view of the wire holder showing the same attached to a post, Fig. 4 represents a rear 50 or inside elevational view of the wire holder, and, Fig. 5 represents a top plan view of the wire holder showing the same as secured to a fence post, the post being shown in section and a portion of the wire holder being broken away.

Although my wire holder is adapted to

be used in connection with fence posts of various forms, I have shown at 1 a fence post in connection with which my invention is particularly adapted to be used, and said post comprises a hollow cylindrical tube, set at its lower end in a concrete base 2, provided at its upper end with a hollow cap 3, the purpose of which will be hereinafter set forth.

The wire holder proper comprises a substantially semicylindrical body 4 provided on its inner face, near the opposite ends thereof, with spaced toothed lugs 5 adapted to engage the metal post, as shown in Fig. 5, for preventing movement of the holder circumferentially of said post. Each pair is substantially arcuate in form and the respective lugs of each pair are oppositely disposed and each lug at its outer end merges 75 with the inner face of the holder, and at its inner end is gradually thickened so as to space the central portion of the inner face of the holder from the post. Although the body of the holder is substantially semi-cylindrical in form, the ends or inner edges 80 of the body lie in parallel relation and are adapted to fit snugly against opposite faces of the fence post when the holder is secured thereto.

As shown the body 4 is provided with oppositely extending substantially cylindrical arms 7, the plane of the outer faces thereof lying in the same plane with the outer face of body 4, thus positioning 90 arms 7 rearwardly of the outer face of the body. As clearly shown in Fig. 3, the sides of the body are provided each with a substantially V-shaped notch extending from one of arms 7 rearwardly. At the 95 point where the apex of the notch occurs, the body is provided with a series of teeth 8, the purpose of which will be hereinafter set forth.

The front face of the body 4 is apertured 100 centrally as at 9, and said aperture occurs midway between arms 7 and in a line therewith, and a lower and upper aperture 10 is provided in body 4, near the lower and upper edges of the same, said apertures occurring in spaced relation to the upper and lower edges of the body and in a line 105 with opening 9.

The fence wire preferably intended to be used in connection with my holder comprises horizontal strands 11 of barbed wire, and vertical strands of twisted or woven

wire 12, although it is to be understood that the exact nature of the wire is optional. At the points where the horizontal and vertical wires intersect the same are knotted, as shown, and the knots fall in vertical alinement longitudinally of the post 1, and when my holder is put in place, opening 9 will be centered over one of the knots, and the opposite ends 6 of the body slid onto the post, thus engaging teeth 8 against horizontal wires 11, as clearly shown in Fig. 5, and thus allowing vertical wires 12 to fall in the spaces between the adjacent ends of toothed lugs 5, and allowing said lugs to firmly grip the fence post. When thus positioned each of the horizontal wires 11 and vertical wires 12 will be engaged between the holder and the fence post and wires 11 will extend out through the V-shaped 20 notches and will be kept from movement longitudinally of the post by the edges of said notches, each of said edges being oppositely beveled, as shown.

In order to secure the holder to the post, I employ a securing wire 13, which at its central portion is looped about the knot formed at the intersectiong point of the horizontal and vertical wires 11 and 12 respectively, and forming a securing knot, and the opposite ends of wire 13 are passed through opening 9, one of said ends being passed under one of arms 7, over one of a pair of lugs 14 formed on the body near said arm and in spaced relation thereto, 35 passed around the post 1 under the opposite arm and between it and its adjacent lug, wrapped around the opposite arm and around the adjacent portion of horizontal wire 11 and has its extreme end twisted 40 around a retaining lug 15 formed on last said arm near its outer end, said lug projecting forwardly therefrom. The opposite end of the securing wire is passed over the last said arm, between the same and the 45 opposite adjacent lug 14, around post 1 in spaced relation with the first said wire end, over the opposite arm and between it and one of its opposite adjacent lugs 14, wrapped around said arm and the adjacent portion 50 of horizontal wire 11 and has its extreme end twisted around retaining lug 15, formed thereon, forming a perfect grip. When the ends of the securing wire are wrapped, as described, it will be noted that 55 portions of the securing wire lie against the beveled edges of the V-shaped notches, said edges thereby co-acting with lugs 14 in preventing movement of the portions of the wire which embrace the post, thereby 60 eliminating all possibility of slack occurring in the securing wire, and thus securing the holder in positive and rigid engagement with the post and thereby preventing movement of the holder longitudinally of the post.

Each of the arms 7 at a point diametrically opposed to its retaining lug 15, is provided with an offset 16, the latter being grooved horizontally, said grooves, however, not extending to the periphery of the 70 arm, and the horizontal wires 11 lie in these grooves, and therefore when the ends of securing wires are wrapped around said horizontal wires, the latter are clamped over said offsets, as shown in Fig. 5. 75

It will be noticed that the inner side of body 4 is conically beveled adjacent opening 9, so as to provide a seat for the knot, or barbed wire or clusters of barbs, occurring at the intersection of the horizontal 80 wires and vertical wires of the fence, according to the nature of the wire used, so that should one of the wire strands be broken, no slack will occur in the remaining portions of that strand. 85

In connection with the wire holders, I use anchoring wires, one method of using the same being shown in Fig. 1, another method being shown in Figs. 2 and 3. With both methods, however, I use an anchoring 90 loop 17, formed as shown in Fig. 1, of a length of wire having a looped portion extending above the concrete base 2, and having the ends of the wire seated in said base, but although I have shown a loop, the anchoring wire may be in the form of a hook, or of a ring, or any other desirable form. In the method shown in Fig. 1, a lower anchoring wire 18 is passed through the lower one of perforations 10, has its ends passed 95 through loop 17 and twisted upon themselves, as shown. An upper anchoring wire 19 is secured at one end through the upper opening 10 in the top one of the series of 100 holders, and has its opposite end twisted about a bail 20 secured to oppositely projecting lugs 21 formed on cap 3. Intermediate anchoring wires 22 have their ends secured in the adjacent openings 10, of the 105 wire holders. In the method shown in 110 Figs. 2 and 3, the anchoring wires have their ends knotted around the knots formed at the intersection of the vertical and horizontal wires of the fence, and pass outwardly through opening 9 and lie along the 115 outside of the wire holders. The particular method of securing the anchoring wires depends upon the nature of the wire used in the fence, whether woven or single wire.

Although I have shown the ends of the lower anchoring wire as twisted together to take up the slack in the length of the anchoring wire sections, it will be understood that I may twist the ends of any one of the anchoring wire sections together, or of a 125 plurality of them, in order to accomplish this purpose.

Although I have described the preferred construction, combination and arrangement of parts of my invention, and the preferred 130

method of operating the same, I may desire to make such changes in the construction, combination and arrangement of parts and such changes in the mode of operation, as do 5 not depart from the spirit of the invention and the scope of the appended claims.

Having thus fully described my invention, what I claim as new and desire to secure by Letters Patent is,

- 10 1. A wire securing means comprising a substantially semicylindrical holder adapted to secure fence wires to a post, said holder provided, with spaced toothed lugs adapted to engage said post, said holder provided 15 with V-shaped notches through which the horizontal wires of a fence are adapted to extend, the vertical wires of said fence adapted to extend between said toothed lugs, oppositely extending arms formed on said 20 holder, in combination with means for co-acting with said arms in securing said holder to the post.
2. A wire securing means comprising a substantially semicylindrical holder adapted to secure the vertical and horizontal wires of a fence to a post, said holder comprising a substantially semicylindrical body, spaced toothed lugs thereon adapted to engage said post, said body provided with substantially 25 V-shaped notches through which the horizontal wires of the fence are adapted to extend, the vertical wires thereof adapted to extend between said lugs, outwardly extending arms on said body, in combination 30 with a wire adapted to be knotted about the intersecting points of said vertical and horizontal wires, the ends of said wire adapted to be passed around said post in opposite directions preferably one under and one over said arms, and adapted to be twisted 35 on said arms over said horizontal fence wires.

3. A wire securing means comprising a holder adapted to secure the horizontal and vertical wires of a fence post said holder comprising a substantially semicylindrical body, means on said body for gripping said post, said body provided with substantially V-shaped notches therein, through which the 40 horizontal wires of the fence are adapted to extend, the vertical wires of said fence adapted to be positioned between said body and said post, said horizontal and vertical wires forming knots at their intersecting 45 point, said body provided with a central opening adapted to be centered over said

knot, said body adjacent said opening being conically beveled to form a seat for said knot, oppositely extending arms formed on said body, retaining lugs formed on said arms, pairs of lugs formed on said body in spaced relation to said arms, said notches having their edges oppositely beveled, said arms provided with grooved offsets, in which said horizontal wires are adapted to lie, a securing wire adapted to be twisted about said knot, said securing wire twisted at its central portion about said knot, and having its ends extending outwardly through said center opening passed in opposite directions one under and one over one of said arms, passed around said post in spaced relation and between said arms and the adjacent lugs on said body, said ends being wrapped around said arms and having 60 their ends wrapped around said retaining lugs, portions of said ends lying against the beveled edges co-acting with the lugs on said body for preventing movement of said securing wire longitudinally of said post, said securing wire having its ends wrapped around said horizontal wire adjacent said offsets for clamping said horizontal wire thereagainst.

4. Means for securing the vertical and horizontal wires of a fence to a fence post, said means comprising a plurality of semi-cylindrical holders adapted to engage said horizontal and vertical fence wires adjacent their intersecting points, said holders provided with openings in their opposite ends, and anchoring wires having their ends passed through said openings said anchoring wires connecting said holders.

5. A fence post having its base seated in the ground, a cap on said post, a plurality of wire holders secured to said post and adapted to engage the horizontal and vertical wires of a fence for securing the same, connecting means between said cap and the uppermost of said holders, an anchoring element secured in said base, connecting means between said anchoring element and the lowermost of said holders, and intermediate connecting means between said holders.

In testimony whereof I hereunto sign my name in the presence of two subscribing witnesses.
